UNITED STATES PATENT OFFICE.

WILLIAM A. SPOTT, OF RICHMOND, VIRGINIA.

ADJUSTABLE YOKE FOR CEILING BANDS.

Application filed February 7, 1924. Serial No. 691,204.

This invention relates generally to supports for electric light fixtures, and particularly to an adjustable yoke for supporting a ceiling band or like globe or shade supporting element from a junction box, pan or like fixture hanger.

The main object of the invention is to provide an adjustable yoke which may be employed for supporting ceiling bands of different sizes from a junction box or pan of any prescribed size, thus enabling a comparatively small sized junction box or pan to be used for supporting ceiling bands which may vary materially in size therefrom, and whereby the necessity of employing a junction box of a particular specified size in connection with a ceiling band of a particular specified size is avoided.

A further object of the invention is to provide an adjustable yoke which is simple of construction, capable of use in connection with junction boxes and ceiling bands of conventional type without changing the construction thereof, and which is readily and conveniently applicable for use for supporting the ceiling band in a firm and secure manner from the junction box and fixture stem.

The invention consists of the features of construction, combination and arrangement of parts, hereinafter fully described and claimed, reference being had to the accompanying drawing, in which:

Figure 1 is a central vertical section through a junction box and a ceiling band supported from the junction box by my improved adjustable yoke.

Figure 2 is a horizontal section on the line 2-2 of Figure 1.

Figure 3 is a perspective view of the adjustable yoke, showing one of the extension pieces removed and disposed in proper relative position for application.

Referring now more particularly to the drawing, 1 designates a junction box, pan or like fixture support adapted to be fitted in a ceiling opening and secured in position in any usual way. Carried by this junction box or pan 1 is a fixture supporting stem 2, which as shown in the present instance is externally threaded at its lower end and internally threaded at its upper end, the latter-named end of the stem engaging the nipple of an anchor frog 3 fastened to the top wall of the junction box or pan. 4 designates a ceiling band of any approved form

or type, that shown in the present instance having the outwardly extending horizontal rim portion 5 provided with the upwardly extending flange 6, said rim 5 being provided at one or more points with openings 7 for the passage of screws 8 whereby it is secured directly, in ordinary practice, to the box 1.

As is well known, the general practice is to provide the lower edge of the box 1 at diametrically opposite sides with portions displaced or bent inwardly to provide fastening lugs, said lugs having internally threaded openings to receive the screws 8, whereby the ceiling band is fastened thereto. This requires that a fixed size of ceiling band be employed in connection with a fixed size of junction box or pan in order that the openings in the pan and lugs of the band may directly register for the reception of the screws 8. Unless these parts are accurately formed it is difficult to make a convenient connection and any slight displacement of the parts, throwing them out of register, causes loss of time and difficulty in uniting the parts together. It is also difficult at times to secure junction boxes and ceiling bands of the specified sizes required, and the use of a specified size of band with a specified size of junction box requires the carrying in stock of different sizes of junction boxes, with resultant inconvenience and trouble in handling and taking care of stock and a considerable increase in overhead cost to the electrical contractor or fixture hanger in being required to keep different sizes of matching pairs of fixture elements.

In order to overcome these objections and difficulties, I provide an adjustable yoke 9 of novel construction whereby ceiling bands of different sizes, within wide limits, may be secured to a junction box or pan of a single given size. As shown, this yoke 9 comprises a flat or substantially flat bar extending diametrically across the open base of the box 1, said yoke consisting of a stationary central section 10 and two extension arms or sections 11 of like construction. The central section 10 consists of a metal plate having an annular or ring-shaped body portion provided with the opening 12 and laterally extending fixed arms 13. The opening 12 adapts the yoke to be fitted on the fixture stem 2 which extends downwardly therethrough and receives a nut 14 for securing

- the yoke thereon and clamping said yoke against the bottom edge of the box 1. The wall of this opening 12 may, if desired, be threaded to engage the threads of stem 2.
- 5 The arms 11 and 13 correspond substantially in length and width and the arms 11 are slidably adjustable on the arms 13 to adapt the length of the yoke to be varied as required. Each arm 13 is provided with 10 a longitudinal guide slot 15 and L-shaped guide fingers 16, and each arm 13 is provided at its inner and outer ends, respectively, with threaded openings 17 and 18 to receive the clamping screws 19 and the ceiling band fastening screws 8, respectively. The screws 19 of the arms 11 pass through the slots 15 in the arms 13 and serve in conjunction with the fingers 16 as guiding means for the arms 11, as well as a means 15 for which said arms 11 may be clamped in adjusted position to the arms 13. The openings 18 are designed to register with the openings 7 in the ceiling band 4 and to receive the screws 8 passing upward through 20 the openings 7, whereby the ceiling band is fastened to the yoke. In practice, the length of the fixed body or central section of the yoke may be such as to extend entirely across and slightly beyond opposite sides of 25 a box 1 of fixed size, allowing adjustment of the arms or sections 11 for attachment of ceiling bands of varying diameters thereto, and the outer ends of the arms 13 may, under such conditions, be arranged to seat 30 within the usual notches above-mentioned in the edge of the box 1, forming a locking connection supplementing that of the nut 14 to hold the yoke in a fixed position and against any possibility of displacement.
- 35 It will be observed from the foregoing that when the yoke is fitted in position upon the stem 2 and against the lower edge of the box 1, the arms 11 may be adjusted for supporting any given size of ceiling band 4 and secured in adjusted position by tightening the screws 19, which, in the adjustment of the arms 11, slide in the slots 15. The openings 18 in the extension arms 11 may thereby be properly positioned for register 40 with the openings 7 of the size of ceiling band 4 to be employed, whereupon by simply applying the screws 8 the ceiling band will be fastened in position. As the yoke 9 is held fixed upon the stem 2 and clamped against the box 1, it will be apparent that the yoke will be firmly fastened in position, affording a reliable and secure support for the ceiling band 4 and the globe 45 or shade carried thereby.
- 50 An adjustable yoke of the character described may, it is evident, be used in connection with any conventional type of junction box or pan and ceiling band without

structural changes in the box or band, and by its use the necessity of employing a specified size of junction box with a specified size of ceiling band is avoided, as a junction box or pan of any given size may be employed in connection with ceiling bands varying to a greater or less extent in size. As a result, the difficulties and inconveniences ordinarily encountered, as hereinbefore stated, will be entirely obviated and the necessity of carrying a multiplicity of sizes of junction boxes and matching sizes of ceiling bands overcome, with manifest advantage to the electrical contractor or fixture hanger. The device also ensures saving of time and other added conveniences in installation work, inasmuch as the yoke may be applied and adjusted for any given size of ceiling band in a very rapid and convenient manner.

Having thus fully described my invention, I claim:

1. A ceiling band supporting element 85 comprising a substantially straight yoke consisting of a central section having a central stem receiving opening and diametrically projecting arms provided with longitudinal slots and angularly bent guide fingers, extension arms slidable on said slotted arms and engaged by said fingers, said extension arms having openings at the inner and outer ends thereof, screws passing through the slots in the slotted arms and 90 engaging the openings in the inner ends of the extension arms, and screws adapted for engagement with the openings in the outer ends of said extension arms for attachment 95 of the ceiling band thereto.

2. The combination with a junction box, a fixture supporting stem carried thereby, and a ceiling band, of an adjustable yoke 100 for supporting the ceiling band from said junction box and stem, said yoke comprising a central section having an opening receiving the stem and provided with diametrically extending arms, each provided with guide members and having a longitudinal slot therein, said arms extending beneath the 110 edge of the junction box, extension arms slidably engaging said slotted arms and provided with threaded openings at their inner and outer ends, screws passing through the slots in the slotted arms and 115 engaging the threaded openings at the inner ends of the extension arms for adjustably fastening the same to said slotted arms, screws passing through the ceiling band and the threaded openings in the outer ends of 120 the extension arms and fastening the band thereto, and a fastening member engaging the stem and holding the yoke thereto and clamped against the junction box.

In testimony whereof I affix my signature.

WILLIAM A. SPOTT,
